FIG. 5.

HERBERT A. DOCKHAM

BY

R. Shaps
ATTORNEY.

UNITED STATES PATENT OFFICE

2,130,617

REFRIGERATOR

Herbert A. Dockham, Crockett, Calif., assignor of
one-third to Hazel L. Groves, San Francisco,
Calif.

Application March 23, 1936, Serial No. 70,344

3 Claims. (Cl. 312—189)

The present invention relates to improvements in refrigerators and its principal object is to provide means for reducing to a minimum the loss of cold air when the door is opened for gaining access to the contents of the refrigerator.

More particularly it is proposed to provide a second or auxiliary door in addition to the conventional main door and to provide this door with a number of openings and windows through which access may be gained to limited sections of the refrigerator without exposing the entire cooling chamber of the refrigerator to draft and to exchange of cooled air with the outside temperature.

15 It is further proposed to make the windows and practically the entire area of the auxiliary door of glass or similar transparent and heat insulating material so that the entire contents of the interior of the refrigerator may be viewed from the outside and selection made before any part of the auxiliary door is opened.

20 It is further proposed to arrange the auxiliary door in such a manner that it will in itself constitute a complete closure for the cooling chamber of the refrigerator.

25 It is further proposed to provide drawers in the cooling chamber and to arrange the auxiliary door with openings through which the drawers may be moved, the entire arrangement being preferably such that the front walls of the drawers lie in the plane of the auxiliary door and cooperate therewith in forming a complete closure for the interior of the refrigerator.

30 It is further proposed to provide a cooling chamber of the refrigerator with shelves or partitions for dividing the same into different compartments and to arrange the window openings of the auxiliary door in such a manner that they substantially register with the compartments so that individual and separate access may be gained to each compartment.

35 Further objects and advantages of my invention will appear as the specification proceeds.

The preferred form of my invention is illustrated in the accompanying drawing in which—

40 Figure 1 shows a perspective view of my refrigerator with the main door open and the auxiliary door closed,

45 Figure 2 a similar perspective view with the main door open and the auxiliary door closed but with certain windows and a drawer open,

50 Figure 3 a similar perspective view with the main door open and the auxiliary door partly open,

55 Figure 4 a vertical section through the door

arrangement taken along line 4—4 of Figure 1, and

Figure 5 a horizontal section taken along line 5—5 of Figure 1.

While I have shown only the preferred form 5 of my invention I wish to have it understood that various changes or modifications may be made within the scope of the claims hereto attached without departing from the spirit of the invention.

10 Apart from the special features of the invention the refrigerator 1 may be made in any conventional manner and the present invention has no reference to the manner or means for cooling the interior of the refrigerator. As a rule a 15 large portion of the upper part of the refrigerator is devoted to the reception of food and this portion is hereinafter referred to as the cooling chamber 2. It is provided with shelves 3 whereby it is divided into different compartments 4 20 and a number of drawers 5 are arranged at the bottom of the chamber. Above the upper shelf 3 there is a special small compartment 6 in which ice cubes are frozen in the conventional manner.

25 The cooling chamber is open in front and has a beveled edge around the opening. A conventional heavy door 7 is hinged to one edge of the opening as at 8 and has a projecting section 9 with a beveled edge 10 adapted to be received within the beveled edge of the door opening. 30 There is enough space between the beveled edges, however, to accommodate the frame of the auxiliary door 11 which constitutes the essential feature of the present invention.

35 The door 11 has a beveled frame 12 of relatively thin material and is hinged to the beveled edge of the door opening as shown at 12', so that when both doors are closed the frame of the auxiliary door lies between the beveled edges of the main door and the door opening.

40 The door is provided with a plurality of windows 13 which are hinged to the door frame 12 as shown at 13' and which are preferably arranged in such a manner as to correspond to the different compartments in the cooling chamber so that 45 access may be gained to the different compartments through the individual windows. Special smaller windows are provided for the smaller compartments on the upper shelf adjacent the ice cube compartment and an opening 14 is left 50 in the auxiliary door for the drawers of the ice compartment and a large opening is provided at the bottom of the frame 12, (see Figure 3) for the drawers 5 so that the drawers may be pulled out without opening the auxiliary door. 55

The drawers are preferably arranged in such a manner that the front walls thereof lie in the plane of the auxiliary door when the latter is closed and completely fill the opening in the door left for them.

5 The manner in which the invention works may be readily understood from the foregoing description. When it is desired to gain access to the cooling chamber as a whole, both the main door and the auxiliary door may be opened. But for all normal operations, as for the insertion and removal of food, the auxiliary door may remain closed and form a closure for the cooling chamber though the main door is open. It fits tightly 10 around the edges so there is no draft. At the same time the contents of the entire chamber may be surveyed through the glass windows before any of the latter are opened. After selection has been made, the operator opens the window 15 through which the selected food may be withdrawn and since the window is small and the time required for opening and closing it very limited there will be very little exchange of air between the inside and outside of the refrigerator. The 20 drawers 5 of the refrigerator and the ice cube compartments may also be opened without opening the auxiliary door.

25 It is apparent that all conventional operation means, such as spring means for opening the doors, latches for closing them and electrical means for releasing the latches may be applied to both doors and the windows without the exercise of invention.

I claim:

30 35 1. In a refrigerator, a housing having a cooling chamber for storing food, a drawer in the cooling

chamber, a door for closing the cooling chamber and a second door inside the first door having an opening through which the drawer may be moved, the drawer having a front wall cooperating with the second door in forming a complete 5 closure for the cooling chamber and arranged to permit the second door to be opened without moving the drawer.

2. In a refrigerator, a housing having a cooling chamber for storing food, a drawer in the chamber, a shelf in the chamber for dividing the same into a plurality of compartments, a door for the chamber and a second door inside the first door and having an opening through which the drawer may be moved and movable windows through 10 which access may be gained to the individual compartments, the second door being made to 15 coact with the drawer in forming a complete closure for the cooling chamber and arranged to permit the second door to be opened without 20 moving the drawer.

3. In a refrigerator, a housing having a cooling chamber, a plurality of drawers in the chamber, a plurality of shelves in the chamber for dividing the same into a plurality of compartments, a door for the chamber and a second door inside the first door and having an opening through which the 25 drawers may be moved and movable windows through which access may be gained to the individual compartments, the second door being 30 made to coact with the drawers in forming a complete closure for the cooling chamber and arranged to permit the second door to be opened without moving the drawer.

HERBERT A. DOCKHAM.
